PRICE COMPUTING MACHINE

Ray C. Niles, Hector, Minn.

Filed May 1, 1959, Ser. No. 55,746

Term of patent 14 years

(Cl. D52—4)

FIG. 1.

FIG. 2.

FIG. 3.

FIGURE 1 is a perspective view of a price computing machine, showing my new design,

FIGURE 2 is a front elevational view thereof; and

FIGURE 3 is an end view thereof.

The undisclosed side of the computing machine is substantially the same in appearance as the side shown except for the operating knob.

I claim:

The ornamental design for a price computing machine, as shown and described.
